DESIGN FOR A RADIO AND TABLE CABINET COMBINATION

Wallace Schier, Forest Hills, and David L. Doggett, Mount Kisco, N. Y., assignors to Federal Telephone and Radio Corporation, New York, N. Y., a corporation of Delaware

Application January 11, 1947, Serial No. 136,076

Term of patent 3½ years

(Cl. D56—4)

To all whom it may concern:

Be it known that we, Wallace Schier and David L. Doggett, citizens of the United States, residing at 150 Greenway Terrace, Forest Hills, Long Island, New York, and Millwood Road, Mount Kisco, New York, respectively, have invented a new, original, and ornamental Design for a Radio and Table Cabinet Combination, of which the following is a specification, reference being had to the accompanying drawing, forming part thereof.

Figure 1 is a perspective view of the cabinet shown with the roll-back facing and pull-out drawer in closed position; and

Figure 2 is a perspective view similar to Figure 1 showing the roll-back facing partially opened exposing a radio dial and about one-half of the loudspeaker grille, and with the lower

drawer portion pulled out exposing a record changer mechanism indicated in broken lines.

The characteristic features of our design reside in the portions shown by means of full lines in the drawing.

We claim:

The ornamental design for a radio and table cabinet combination, substantially as shown and described.

WALLACE SCHIER.
DAVID L. DOGGETT.
